ROLLING MILL CONTROL

Frank J. Wood, New Rochelle, N. Y., assignor to
Erwin Loewy, New York, N. Y.

Application July 9, 1947, Serial No. 759,786

3 Claims. (Cl. 80—38)

1

This invention relates to rolling mills and particularly to a drive and control for a four-high type rolling mill adapted for use in the high speed rolling of thin metals, such as metal foil.

A rolling mill is an expensive machine, and, therefore, it is desirable to be able to increase the productivity thereof whenever possible, and particularly, when a low cost item, such as foil, is being rolled, the greater the quantity of foil produced by a mill, the greater the reduction in cost of the foil. Also, by speeding up the rolling mill, one mill can perform the task of several mills. The standard speed now in use for foil mills is about 400 feet per minute. By the use of the invention described herein, this speed can be increased to as much as 3,000 feet per minute which will give a significant increase in output of a mill.

One of the principal objects of the invention is to materially increase the speed of operation of a rolling mill.

Another of the objects of the invention is to produce a smoother and more perfect product at the aforementioned high operating speeds of a rolling mill.

Another object of the invention is a simplified manner of controlling the acceleration, deceleration, and operation of a rolling mill.

In prior practice, rolling mills of the four-high type have been driven through the outer rolls alone, the inner rolls alone, or by an interconnection or drive of all four rolls. It has been found, however, that these arrangements are not entirely satisfactory. At high speeds of operation, an imperfect product will be rolled, particularly in thin material where the thickness of the material is in the range of 0.00025 of an inch. When a rolling mill is operated, the backing roll is made considerably larger in diameter than the work roll, the ratios of the diameters being, for example, two or more to one. There is a thin film of lubrication normally on the rolls, the coefficient of friction between rolls is small, and there is substantially only a line contact between the rolls. In the acceleration of the rolls up to speed, it is thus apparent that the force between the rolls is along a line contact and that the coefficient of friction is small and thus the rolls will tend to slip relative to each other, it being remembered that the moment of inertia of the rolls varies as the square of the radius thereof. When the back-up rolls are accelerated and decelerated by friction from the work rolls, skidding of the work roll against the large mass of the back-up roll will scratch the highly finished

2

surface of the work rolls. It is necessary, therefore, due to the large inertia of the back-up roll, to drive the back-up roll during acceleration and deceleration in high speed operation. Difficulty arises when the speed of the work roll is changed during the rolling operation because there will be a skidding action between the backing and the work rolls and this will tend to scratch or roughen the work roll surface. On thin gauge material, the depth of the scratch or roughening of the roll often will represent a substantial proportion of the thickness of the foil to be rolled and thus will mark the foil and also may cause breakage. Attempts have been made to minimize the slip or skidding by using excessive pressure between the rolls, but this results in many problems.

When the rolls are all connected together and driven simultaneously by gearing, difficulty is involved at high speeds due to the unequal roll diameters. One of the features of the present invention is to drive all four rolls during the acceleration period and then to drive only the work rolls during rolling. A friction type clutch is provided in the drive connections to the two back-up rolls, the clutch being engaged during the accelerating period and then disengaged when the mill reaches its operating speed.

Another feature of the invention is to reconnect the back-up rolls to the drive mechanism as the rolling mill is decelerated to a stop. In one aspect of the invention, an electrically operated clutch is used although a suitable mechanically operated clutch also may be employed.

These and other objects, features, and advantages of the invention will become apparent from the following description and drawings which are merely exemplary.

Fig. 1 shows a schematic front view of the rolling mill with the drive mechanism of the present invention.

Fig. 2 shows a wiring diagram of one type of control that may be used.

Fig. 3 is an enlarged diagrammatic view of the magnetic clutch used in the arrangement of Fig. 1.

Fig. 4 is an enlarged view of a mechanically operated clutch that can be used in place of the clutch of Fig. 3.

Fig. 5 is a fragmentary view of Fig. 2 showing the control generator replaced by a fly-ball generator.

In the preferred form of the invention, the rolling mill stand is indicated diagrammatically at 10 having housings 11 supporting the bear-

ings in the usual manner, the top backing roll being shown at 12 and the bottom backing roll being shown at 13. The upper working roll 14 is contacted by backing roll 12 and the lower working roll 15 is in contact with the lower backing roll 13. A suitable screw-down apparatus is indicated at 9. Drive motor 16 is connected to the diagrammatically shown gear box 17. Small drive pinion 18 connected to the drive motor shaft meshes with large gear 19, gear 19 being connected to lower working roll pinion 20. Pinion 20, in turn, is connected through conventional connecting elements 21, 22 and 23 with the bottom working roll 15. Upper working roll pinion 24 is driven by lower working roll pinion 20 and is connected through the conventional connecting elements 25, 26, and 27 with the upper working roll 14. Backing roll gears 28 and 29 are in mesh with pinions 20 and 24, respectively. Pinions 28 and 29 are connected to the driving elements or hubs of the friction clutches 30 and 31.

In the preferred form, a magnetic clutch is used, but, as explained hereafter, a mechanically operated clutch also can be employed. A magnetic clutch is seen in Fig. 3 wherein drive hub 32 is keyed to shaft 33, shaft 33 being connected to gear 29. The drive hub 32 has an annular electromagnet arrangement 34 mounted thereon. The driven hub 35 has a bushing 36 therein so that the driven hub 35 and bushing are rotatable on the end of stub shaft 33, the driven hub 35 having connected to the connector 37. Armature 34a is longitudinally movable on the drive hub 32, such movement being effectuated by energization of electromagnet 34, commutator elements 34b being provided for supplying electric current to said electromagnet. Friction plates 38 are connected with the slidable armature 34a, and friction plates 39 are connected with the driven hub 35. When the armature 34a is moved to the left (Fig. 3) by energization of the magnet 34, plates 38 and 39 will be tightly engaged with each other and against the flange 35a of the driven hub 35 so as to transmit rotation of the shaft 33 to the connector 37 and thence to the upper backing roll 12. A similar drive is provided through the lower friction clutch 31 through connector 40 to the bottom backing roll 13. Other types of magnetic clutches may be used.

It is thus apparent that the working rolls are positively driven or have torque positively applied thereto at all times when the drive motor is energized, whereas the backing rolls are positively driven only when the clutches are energized.

As shown in Fig. 4, the magnetic clutch arrangement can be replaced by a mechanically operated clutch wherein a yoke 41 exerts pressure on the slidable drive hub 42 so that the clutch plates 43 are engaged in such a manner as to transmit power from the gear drive to the back-up roll. The yoke 41 may be operated hydraulically, by a solenoid, or in any suitable manner.

One form of control circuit which can be used is seen in Fig. 2 wherein three push buttons or control switches are employed, it being understood that various arrangements of buttons or switches can be provided. In the arrangement shown, the start push button is pressed to start operation of the mill whereby the mill is accelerated to operating speed by a positive driving of all of the rolls, the positive drive to the back-up rolls being interrupted when the mill has

reached operating speed. The second push button can be used to interrupt the supply of energy to the working rolls and to positively reconnect all of the rolls together so as to cause deceleration thereof together, the clutches being re-energized for this purpose to reconnect the backing rolls through the gearing to the working rolls. The third button or reset button is pressed to completely de-energize the circuit including the magnetic clutches, said magnetic clutches having been energized during deceleration.

Upon pressing start button 44, the roll drive motor switch solenoid 45 will be energized through lead 100, switch contacts 52, closed switch contacts 50, solenoid 45 and lead 101, leads 100 and 101 being connected to the direct current leads from generator 47. Closing of drive motor switch 46 will connect the direct current generator 47 with the direct current drive motor 16. As is well known in the art, direct current generator 47 is driven by alternating current motor 48, exciter 49 also being connected to said alternating current motor 48. The exciter 49 is used to control the field 16a of the main drive motor 16 and thereby to assist in control of the speed of the main drive motor.

Operation of drive motor switch solenoid 45 will cause switch contacts 104 to be closed and thus establish a holding circuit for drive motor switch solenoid 45, the holding circuit extending from lead 100, switch contacts 52, lead 103, switch contacts 104, solenoid 45 and lead 101.

The pressing of push button 44 also will close switch contacts 51 to energize the master magnetic clutch switch solenoid 55, the circuit therefor being through lead 100, reset switch 71, lead 105, master magnetic clutch switch solenoid 55, lead 106, switch contacts 51 and lead 101. Energization of solenoid 55 will cause closing of switch contacts 57 and thus establish a holding circuit for solenoid 55 and the master magnetic clutch switch 56. The holding circuit for solenoid 55 is through lead 100, lead 105, solenoid 55, lead 106, lead 107, holding switch 57, lead 108, and lead 101. The clutch de-energizing switch contacts 59 normally are closed so that closing of master magnetic clutch switch 56 will cause energization of the magnetic clutch coils 111, energy being supplied through lead 109, switch 59, lead 110, coil 111, lead 112 and master clutch switch 56. Drive motor 16 positively drives working roll 12 through gear 73 and gear 73 drives gear 74. Gear 74, in turn, drives backing roll 75 positively through the magnetic clutch 111 when the clutch is energized. The gears and rolls in Fig. 2 are shown schematically, and it is to be understood that a second working roll, backing roll, and magnetic clutch are provided, the magnetic clutch of the second backing roll being connected to leads 118.

Drive control generator 62 is driven from the shaft of motor 16 through some suitable driving means 63 which may consist of a chain drive or gearing. The field 62a of drive control generator 62 is adjustable by means of rheostat 64. Drive control generator 62 is connected to clutch de-energizing solenoid coil 66 through leads 113. When the drive motor 16 and rolls reach a predetermined operating speed, solenoid coil 66 will be energized sufficiently to open switch 59, thereby de-energizing the magnetic clutch solenoid coil 111 and thus disconnecting the positive drive of gear 74 to the backing roll 75.

When it is desired to stop the mill, stop switch

53 is pressed. This will open the holding circuit to the main switch solenoid 45 and thereby cause main switch 46 to open, thus de-energizing drive motor 16. Contacts 73 of the stop button will be closed which will complete a circuit through the decelerating magnetic clutch switch solenoid 76, the circuit being completed from lead 112 through lead 113, closed switch contacts 54, closed switch contacts 73, lead 114, solenoid 76, lead 115 and lead 109. This will cause energization of the decelerating magnetic clutch solenoid and close the decelerating magnetic clutch switch 71. The holding switch contacts 78 also will be closed to provide a holding circuit around the stop button contacts 73, the holding circuit being established from lead 112, switch contacts 54, lead 116, switch 78, lead 117, lead 114, solenoid 76, lead 115, and lead 109. The solenoid 55, during this operation, still remains in energized position so that the main magnetic clutch switch 56 remains closed. Operation of the solenoid 76 will thus re-energize magnetic switch clutch coil 111 so as to positively reconnect the backing rolls and the working rolls during deceleration. As the rolling mill slows down, switch 59 also will close providing two paths to the magnetic clutch coil 111.

In order to de-energize the entire circuit, it is necessary to operate the reset push button 71 which will de-energize the magnetic clutch switch solenoid 55 and thus de-energize the magnetic clutch 111 and the decelerating magnetic clutch solenoid 76.

A flyball governor arrangement 79 (Fig. 5) can be driven by a suitable connection 63 with the main drive motor operating shaft. The flyball governor 79 may be connected to a switch arrangement 80 which will govern the energization of magnetic clutch solenoid 82 by a source of energy 81. Thus, when the drive motor 16 reaches operating speed, switch 80 will close and source of energy 81 will cause opening of switch 83, switch 83 being identical to switch 59 in Fig. 2 and serving to de-energize the magnetic clutch 111 and thereby interrupt the positive drive of the backing rolls.

The power supply source is shown diagrammatically at 84 in Fig. 1 with the control box 85 containing the electrical circuits involved, the drive control generator corresponding to 62 of Fig. 2 being shown in box 86. The push buttons are shown diagrammatically connected to the control box 85 and are operable, as just described, to start, stop, and reset the control circuit.

When the machine is to be operated, it is first brought up to speed by pressing start button 44. This will cause drive motor 16 to be energized and all of the rolls to be driven as the speed thereof is accelerated. As explained previously, this is necessary or desirable because of the inertia of the rolls, which is particularly significant at the high operating speeds of the device. After the device has reached the desired operating speed, the clutches 30 and 31 will disconnect the positive drive or direct application of torque to the backing rolls and thus only the work rolls will be positively driven. The rolling mill then is in condition for carrying out rolling operations. As explained previously, the relative inertias of the large size backing rolls and the working rolls is such that skidding is liable to occur during high speed rolling operation, and by the use of the herein-described system and method of operation of the mill, previously known serious difficulties of high speed operation, espe-

cially when rolling thin material, are eliminated.

When it is desired to decelerate the rolling mill or bring it to a stop, pressing of push button 53 will cause the clutches to reconnect the backing rolls with the driving gear and, at the same time, will cut off the driving power to the gear drive, thus serving to rapidly decelerate all of the rolls together. If the reconnection was not made, the large inertia in the backing rolls might cause serious difficulties in the roll operation due to slippage between the backing rolls and the working rolls during deceleration.

The particular control system used for governing operation of the mill can be carried out by various circuits, and various types of clutches can be used, it being understood that those shown herein are merely exemplary. It is thus apparent that the details of construction depicted and described may be varied without departing from the spirit of the invention as defined in the appended claims.

What is claimed:

1. In a control system for a rolling mill having working and backing rolls, the working and backing rolls being in frictional contact with each other, material being passable between said working rolls, a switch shiftable to energize a driving motor, said driving motor being positively connected to said working rolls, clutch mechanism connecting the driving motor with said backing rolls, a second switch mechanism operable when said first switch mechanism is shifted to activate said clutch mechanism and connect said drive mechanism positively to said backing rolls, and a roll speed switch mechanism connected with said second switch mechanism operable when said rolls have reached a predetermined speed deactivating said clutch mechanism and interrupting the positive connection of said driving mechanism to said backing rolls, so that said backing rolls then are driven only by frictional contact with their respective working rolls.

2. In a control system for a rolling mill having working and backing rolls, the working and backing rolls being in frictional contact with each other, material being passable between said working rolls, a switch shiftable to energize a driving motor, said driving motor being positively connected to said working rolls, normally deactivated clutch means connecting said driving motor with both of said backing rolls, a second switch mechanism operable when said first switch mechanism is shifted, activating said clutch means to connect said drive mechanism positively to said backing rolls, a roll speed switch mechanism connected with said second switch mechanism operable when said rolls have reached a predetermined speed deactivating said clutch means and interrupting the positive connection of said driving mechanism to both of the backing rolls so that the backing rolls are driven only by frictional contact with said working rolls, and a stop switch connected with said second switch mechanism and operable to reactivate said clutch means to reconnect said drive mechanism to both of said backing rolls and to interrupt the energization of said drive motor.

3. In a high speed four high rolling mill suitable for rolling thin foil or the like, said mill having working and backing rolls, the working and backing rolls being frictionally contactable with each other, working roll driving mechanism connected with both of said working rolls at all times during rolling, selectively operable driving clutch means connectable with said backing

rolls only during acceleration and stopping of the mill for positively connecting said backing rolls to said driving mechanism, said backing rolls being driven at other times by frictional contact with their working rolls, control means connected to said clutch means and having mechanism operable during acceleration to activate said clutch means and connect said backing rolls to said driving mechanism and having mechanism operable when the mill is to be stopped to deactivate said clutch means and connect said backing rolls to said driving mechanism, and speed responsive means connected with said control means interrupting activation of said clutch connection of said backing rolls to said driving mechanism when they have reached a pre-determined speed, so that

said backing rolls are driven only by frictional contact with the working rolls.
